UNITED STATES PATENT OFFICE.

STANLEY ANTHONY, OF BOSTON, MASSACHUSETTS.

CARD-INDEX.

1,340,140.

Specification of Letters Patent. Patented May 18, 1920.

Application filed March 19, 1919. Serial No. 283,577.

To all whom it may concern:

Be it known that I, STANLEY ANTHONY, a citizen of the United States, residing at Boston, county of Suffolk, State of Massachusetts, have invented an Improvement in Card-Indexes, of which the following description, in connection with the accompanying drawing, is a specification, like characters on the drawing representing like parts.

9 This invention relates to card indexes of that type which comprises a frame, a plurality of holders or card carriers removably sustained thereby, and cards removably carried by the holders or carriers.

15 One of the objects of my present invention is to provide an improved holder or carrier for cards on which two or more cards may be supported and which is so constructed that either one of the cards can be removed from or replaced on the carrier without disturbing the other card. One advantage of this improvement is that it enables twice as many cards to be used in one frame than would be possible if only one card could be attached to each carrier, and hence it provides means whereby the capacity of an ordinary card index of this type may be doubled by using two cards for each carrier instead of one. Another advantage which 25 results from this construction is that it provides for readily expanding the card index as necessity requires. If, for instance, the card index as originally put in use had one card on each carrier, each card relating to a 30 different name or subject, and through expansion of business it was found that one card was insufficient to contain all the data relative to any one particular subject, then another card could be readily attached to 35 the carrier containing the filled card so that the surplus data or material can be placed on said second card. Thus the use of an additional card for any one name or subject does not involve the use of an additional 40 carrier.

45 Another object of my invention is to provide an improved card index of the type in which two cards are or may be suspended from the same card carrier and which is so constructed that each of the cards has at its lower edge a space to receive the name or subject to which the data on the card appertains, and which space is visible at all times. This construction makes it possible to attach 50 to each carrier two cards relating to different names or subjects if desired.

Another object of my invention is to provide an improved carrier or holder for cards which is made from a strip of sheet metal and which is constructed so that it can be 60 readily removed from the frame.

Other objects of the invention are to improve generally card indexes, all as will be more fully hereinafter set forth.

In order to give an understanding of my 65 invention, I have illustrated in the drawings some selected embodiments thereof which will now be described, after which the novel features will be pointed out in the appended claims.

In the drawings, Figure 1 is a perspective view of a portion of a card index embodying my invention;

Fig. 2 is an enlarged section through one side of the frame or holder;

Fig. 3 is a perspective view with a part broken out of one of my improved holders or carriers;

Fig. 4 is a view of the two cards which are placed on any carrier with the central 80 portion of the cards broken out and with one hinge portion shown unfolded and in the form of a tab;

Fig. 5 is a section on the line 5—5, Fig. 4;

Fig. 6 is a fragmentary perspective view 85 showing a different embodiment of the invention;

Fig. 7 is a sectional view similar to Fig. 2 showing the modified form of the invention.

1 indicates the frame of the card index and 2 indicates the cards. These cards are secured to flexible holders or carriers 3 which are removably retained in the frame 1, said frame having the usual lips or flanges 95 4 at its edges beneath which the ends of the flexible holders or carriers are received, all as usual in card indexes of this type.

The various holders are arranged one above the other, so that the cards which are 100 supported thereon will have an overlapping relation with the lower edge of each card visible below the lower edge of the card next above it.

My improved holder or carrier 3 is made 105 from a strip of sheet metal of the requisite length, and it is constructed with ends which have a dimension from back to front greater than the thickness of the strip. The lips 4 of the frame 1 are so constructed that the space 110 6 between the lips and the body of the frame is somewhat greater than the thickness of

the strip from which the holder 3 is made, and in order to prevent any holder from slipping down behind the next adjacent holder I propose to make the ends of the 5 holder of increased thickness. This can be done in various ways. One way is to bend the ends of the strip back on the body thereof as shown at 5 Fig. 3 thereby providing ends of double thickness. Another way is 10 that shown in Fig. 6 wherein the ends of the body are bent laterally as shown at 12, these laterally bent portions being of a length to extend across the space 6. In both forms of the invention the increased trans- 15 verse dimension at the ends of the holders prevents them from becoming wedged behind each other and serves to retain them in their proper relative positions.

Each holder or carrier has pintles struck 20 up therefrom on which the cards are hung. I propose to make each carrier with two pairs of pintles, the pintles of one pair being indicated at 7, and those of the other pair at 8. With this construction two cards 25 can be hung from each carrier, one card being sustained on one pair of pintles and the other on the other pair of pintles.

Each card 2 has two hinge portions 10 adapted to receive a pair of pintles and each 30 card is placed on the pintles by slipping one hinge over one of the pintles and bending the card centrally sufficiently to permit the other hinge to be slipped over the other pintle when the card is straightened. Any 35 card can be removed by simply reversing these operations.

Some cards will have the hinge portions 10 spaced so as to detachably engage the pair of pintles 7, while other cards will have 40 their hinge portions situated so as to detachably engage the pintles 8. Two cards can thus be supported from each carrier 3 and because each card is sustained on its own pair of pintles, either card can be re- 45 moved without disturbing the other card.

While the hinge portions 10 of each card may be made in various ways, I will preferably make each hinge portion from an integral portion of the card. This can con- 50 veniently be done by forming each card in the first instance with two tabs 11 and then folding the tabs over to form the hinge portions, the ends of the tabs being secured to the body of the card by means of a suitable 55 adhesive or some other fastening device.

The holders or carriers 3 are flexible or resilient so that by bending them away from the frame at their central portion the ends can be withdrawn from the lips 4. In order 60 to facilitate the removal of any carrier, I propose to make it so that some portion thereof intermediate of its ends is spaced or separated from the body of the frame so that a person can readily grasp such por-

tion to bend the carrier centrally a sufficient 65 amount to permit the ends to be withdrawn from the lips 4. This spacing or separating of some portion of the carrier from the frame may be provided for in various ways. One convenient construction is that herein 70 shown wherein the central portion 9 of each carrier is offset or bent outwardly to occupy a position in front of the plane of the rest of the carrier. Thus when the carrier is placed in the frame it will rest against the 75 back thereof, but the portion 10 will be separated from the back. Since the carriers are flexible, the operation of removing any carrier involves pressing backwardly the central portion of the carriers above and 80 below the one desired to be removed so that a person can grasp the portion 9 of said latter carrier between his thumb and finger thereby to draw the carrier outwardly.

My improvements involve the use of two 85 cards on each carrier and is particularly applicable to card index systems that require frequent readjustment because of additional data which it is desired to place on the cards and especially where such ex- 90 pansion may involve the use of more than one card for any particular name or subject matter. Under such circumstances the cards which are used in the first instance in the system may be those which will be sus- 95 tained on the pintles 7 of the holders and as the card relating to any one subject or name becomes full and another card is required for additional data; a second card adapted to be secured to pintles 8 may be applied to 100 the holder, thus providing two cards. This second card may, if desired, be of the same length as the first card or may be longer or shorter so that its lower edge will not come into alignment with that of the first 105 card.

My invention is also applicable to card index systems where one card only is sufficient to receive the data for any name or subject, for by properly making the card, 110 it is possible to support two cards on any one carrier and yet have the data or name-bearing space at the lower edge of each card visible. In Fig. 1 I have illustrated two cards suspended from the top carrier. One 115 of the cards has at its lower edge at one end a space 32 to receive the name or subject to which the data on the card appertains, and the other card has at its lower edge on the opposite side a similar space 120 33. The first-named card is cut away at its lower edge opposite the portion 33, as shown at 34, and the second card is cut away at its lower edge, as shown as 35 opposite the space 32. With this arrangement the two spaces 32, 33 for the two cards are 125 in alignment, but they are both visible and hence these two cards can be used for differ-

ent subject matter, with this arrangement of cards it is possible to hang two cards on all the carriers if desired, thus doubling the capacity of the card index and yet have 5 the name or data-bearing space of all the cards visible.

In using card indexes of this type it frequently happens that an entry is made in ink either by hand or on the type-writer which 10 it is desired to erase. Where the cards are made of ordinary paper the erasure of an ink entry is often difficult and rather than erase such an entry the clerk frequently makes out an entirely new card. In order 15 to avoid this necessity, I propose to make my index cards with a washable surface so that if it is desired to erase any ink entry, the surface of the card can be cleaned by simply washing it with a damp sponge or 20 cloth. This washable surface might be attained in various ways. One would be to make the card from celluloid material which is constructed to take ink. An opaque celluloid or celluloid composition will, of course, 25 be preferable to a transparent material.

While I have herein illustrated some selected embodiments of the invention, I wish to state that the invention is not confined to the construction shown as the latter may 30 be varied in various ways without departing from the spirit of the invention as set forth in the appended claims.

I claim:

1. In a card index, the combination with 35 a frame, of a plurality of card holders removably sustained thereby, one above the other, each holder having two pairs of card-supporting pintles and a card pivotally hung on each pair of pintles.
2. In a card index, the combination with 40 a frame, of a plurality of card holders removably sustained therein, one above the other, each holder having two pairs of card-supporting pintles and a card pivotally hung on each pair of pintles, each card being 45 capable of removal from its pintles without removing the other card.

3. In an index, the combination with a frame, of a plurality of card holders removably sustained thereby, each holder having 50 provision to engage detachably two cards either of which can be removed from the holder without disturbing the other card.

4. In a card index, the combination with a frame having retaining lips at its edges, 55 of a plurality of card holders retained in position by said lips, each holder being formed from a strip of sheet metal and having card-receiving pintles struck up therefrom, the ends of each holder that are 60 retained under the lips having a dimension from front to back greater than that of the body thereof, and cards carried by said pintles.

5. In a card index, the combination with 65 a frame having a back and retaining lips at its edges, of a plurality of resilient card carriers extending across the frame and having their ends retained beneath said lips, each carrier being made of a strip of sheet metal 70 which has some portion thereof intermediate of its ends offset forwardly from the plane thereof to provide means by which the carrier can be readily grasped to remove it 75 from the frame.

6. A holder or carrier for cards of a card index system, said holder being made of a strip of metal and provided with means to support detachably a card, the central portion of said holder being offset to the front 80 of the plane of the body thereof.

7. In a card index, the combination with a frame, of a plurality of holders removably sustained thereby, one above the other, a plurality of cards suspended from each 85 holder, each card having at its lower end a title- or name-bearing portion, said name-bearing portions of all the cards on each holder being situated in alinement and all of said portions of all the cards being 90 visible.

In testimony whereof, I have signed my name to this specification.

STANLEY ANTHONY.
